UNITED STATES PATENT OFFICE

2,121,088

BRASSIÈRE AND THE LIKE

Dee La Rue, Chicago, Ill.

Application September 17, 1934, Serial No. 744,306
Renewed November 13, 1937

3 Claims. (Cl. 2—42)

This invention relates to improvements in brassières and relates particularly to what may be called mother's brassières, or lying-in brassières or nursing brassières.

5 The advantages of my invention will be realized, especially by the nursing mother of a new born infant. Such a mother is in about as weakened a state as she could be and it is desirable to eliminate as much movement and inconvenience of all kinds as is possible for the best interest of both the mother and the child.

The brassière arrangements now in use for such purposes are attended with much disadvantage as is well known. Much lifting and shifting of the body is necessary to arrange for the nursing of the child, and also an unnecessary large breast area is exposed with attendant danger from cold and also embarrassment, besides other well known disadvantages.

20 My object has been to provide a brassière whereby a mother may nurse a child with a minimum of movement and inconvenience, and with a minimum of exposure. Another object has been to provide a brassière which will be self adjustable easily, both around the waist and over the shoulders and one which will be easily removable. In addition, another object has been to provide a brassière which will properly retain and position the breasts, giving the necessary lift.

30 To this end I have illustrated in the preferred form selected, a brassière having a pair of openings for the breasts and a pair of flaps adapted to be cross hooked to close the brassière and protect the breasts and effectively contain and position the breasts, and either or both of which may be unfastened to provide for convenient and safe nursing. I have also provided for fastening the brassière by simple means in the front whereby it may be easily unfastened for self removal if desired. I have provided also for simple self adjustment around the waist and over the shoulders.

40 After use for nursing the flaps may be stitched if desired and the brassière may be used in that condition permanently to retain the advantages of its natural uplift and positioning and other features.

45 Another object has been to provide a device of the kind which will be simple in construction and reasonable in cost to manufacture.

50 Other objects will appear hereinafter.

The invention consists in the combinations and arrangements of parts hereinafter described and claimed.

55 The invention will be best understood by ref-

erence to the accompanying drawing forming part of this specification, and in which:

Fig. 1 is a front perspective view showing the device applied to the body;

Fig. 2 is a side elevational view taken on the line 2—2 of Fig. 1;

Fig. 3 is a view similar to Fig. 1, except that the adjustable flap is removed;

Fig. 4 is a rear elevation of the entire device;

Fig. 5 is an enlarged view of one breast portion and side with the flap closed;

Fig. 6 is a view similar to that of Fig. 5, with the flap turned back;

Fig. 7 is an enlarged sectional view taken on the line 7—7 of Fig. 5 of the adjustable inset of 15 my invention; and

Fig. 8 is a view of the modified form of shoulder strap arrangement.

The preferred form selected in the drawing to illustrate the principle of my invention comprises a brassière 10 having a back body portion 11, a left front body portion 12 and a right front body portion 13. The back body portion 11 is provided with shoulder strap portions 14 having eyelets 15. The shoulder strap portions 14 are narrow as shown and are broadened at 16, as shown particularly in Fig. 4, at the bottom as they merge into the back body portion 11 to prevent distortion as will be manifest. The back body portion 11, and practically the entire brassière 10 is provided with a reinforcing band 17 to strengthen the device and prevent distortion. The back body portion 11 is cut to form the relatively low cut back, as shown, and is deeply cut, as shown, to provide right and left underarm portions 18. Each of the underarm portions 18 is sewn to an inset 19, each side of which is hemmed as at 20, and each hem 20 is provided with eyelets 21, as shown in Figs. 5 and 7.

The back body portion 11 is in one piece in the form shown, except for the band 17, and the portion 11 is adapted to be laced to the front right and left breast portions as will appear hereinafter.

The two body portions 12 and 13 are substantially the same and description of one will suffice. Taking the left front body portion 12; it is made in one piece in the preferred form shown, and has an integrally formed hooked strap portion 22 and hooks 23 for engagement with one strap portion 14. The left front body portion 12 is provided with an aperture 24 which is fitted around the central portion of the left breast and through which the central portion of the 55

breast may extend outwardly. A reinforcing band 25 is sewn around the aperture 24.

The portion 12 in the preferred form illustrated is made up of three pieces, 26, 27 and 28, 5 cut on curves and stitched together to form a pocket 29 as shown in Fig. 2, which structure and result will be manifest to those skilled in the art, without further explanation. A dart 30 is also provided in the body portion 12 to complete 10 a desired pocket structure and make a desirable fit.

The body portion 12 is also provided with a straight edge hemmed portion 31 with eyelets 32, and of course, it will be understood from the 15 drawing that the other body portion 13 is similarly constructed with a seamed edge portion 33 with hooks 34. The arrangement is such that the hem portion 31 laps over on the hem portion 33 with the hooks and eyelets engaging 20 invisibly to close the front of the brassière and also to make the brassière easily removable.

Means are provided, for example, in the case of a nursing mother, for concealing and protecting the breast when she is not nursing, and 25 for conveniently exposing the breast in nursing without removing or opening the brassière proper.

To accomplish the result of the preferred form shown, I provide a flap 35 on a body portion 30 12 and another flap 36 on the body portion 13. These flaps are particularly illustrated in Figs. 1, 4, 5 and 6. Each flap is substantially the same and the description of one will be sufficient. The flap 35 is composed of three pieces, 37, 38 and 39 in the preferred form shown, and they are seamed together by seams 40. The piece 37 is provided in the form shown with a pair of darts 41 and the pieces are cut on curves as shown in the preferred form and darts are arranged as 40 will be understood by those experienced in the art, to form a pocket 42 in each flap, said pocket 42 being clearly illustrated, particularly in Fig. 2. The body portion 12 and the flap 35 and the inset 19 are stitched together in a seam 43 and 45 the seam 43 is provided with eyelets 44. The flap 35 and the body portion 12 are stitched also, as at seam 45 shown in Fig. 4 and are stitched also as at seam 46, shown in Figs. 4 and 6.

By this arrangement, the flap is partially sewn 50 to the body portion 12. The arrangement of the seams 45 and 46 particularly, completes formation of the pocket 42 so that when the flap is hooked as hereinafter described it will lift and properly position and retain the breast. The 55 unstitched or free end of the flap as illustrated in Fig. 6 is provided with a hook adapted to engage an eyelet 48 on the body portion 12. In the same manner, the other flap is provided with a hook and the body portion 13 is provided 60 with an eyelet for engagement. It will thus be seen that when the flaps are lapped and hooked as shown in Fig. 1, the desired positioning and lift will be accomplished. It will be manifest that the flap registers with and covers the aperture 65 24 to effectively protect the breast in hooked condition and may easily be unhooked to conveniently expose only a minimum necessary breast area, thereby also protecting the breast.

Laces 49 are provided for each pair of eyelets 70 21 and 44 for adjustment. By this means it

will be manifest that lateral adjustment may be accomplished very easily by the user herself and this adjustment may cover one or more sizes each way.

In Fig. 8, a modification of the shoulder strap means is shown, and the body portions 12 and 13 have modified pointed strap engagement portions 50 and the back portion 11 has modified pointed strap engaging portions 51 provided with buttons 52. An elastic strap is provided with a 10 plurality of button holes 54 for vertical adjustment. By this means the user may conveniently make effective self adjustment. The importance of this self adjustment laterally and vertically should be manifest, but its full importance will 15 be realized by those who have had practical experience with the devices now in use on the market.

My arrangement eliminates practically all of the necessary shifting and other inconveniences 20 attached to such devices.

The operation of the device will be manifest without explanation.

I have, in the preferred form shown, provided 25 illustrated forms of flaps and body portion arrangements and various cuts and darts to form the pockets and various means of adjustment, but it should be realized that these features are merely forms used to illustrate the invention 30 and may be varied as the particular arrangements that I have shown are not necessary. I, therefore, do not wish to be limited to the precise details of construction set forth, but desire to avail myself of such variations and modifications 35 as come within the scope of the appended claims.

Having thus described my invention, what I claim as new and desire to secure by Letters Patent is:

1. In a device of the kind described, a brassière body portion provided with a pair of pockets for containing parts of the body and provided with a circular opening in each of said pockets said brassière body portion also having means adapted to provide for a vertical support of said parts of the body, flaps laterally secured to said body portion adjacent said opening said flaps being formed in a pocket-like shape to provide auxiliary supporting means for supporting said parts of the body in a vertical and lateral manner, and detachable securing means for the ends 40 of said flaps said securing means being adapted 45 for the overlapping of the free ends of said flaps for vertical and lateral support.

2. In a device of the kind described, a brassière body portion provided with a pair of openings, 55 flaps laterally secured to said body portion adjacent said openings, and detachable securing means for securing the free ends of said flaps with one flap overlapping the other.

3. In a device of the kind described, a brassière body portion provided with a pair of openings, flaps laterally secured to said body portion adjacent said openings, said flaps being formed in a pocket like shape to provide auxiliary supporting means for supporting parts of the body, and detachable securing means for securing the free ends of said flaps with one flap overlapping the other.
